Primary Examiner — Kevin Rudzinski(74) *Attorney, Agent, or Firm* — King & Spalding LLP**(57) CLAIM**

The ornamental design for a troffer luminaire, as shown and described.

DESCRIPTION

FIG. 1 is a perspective view of a troffer luminaire, showing my new design;

FIG. 2 is a bottom view thereof;

FIG. 3 is a cross-sectional view thereof;

FIG. 4 is a perspective view of another new ornamental design for a troffer luminaire;

FIG. 5 is a bottom view of the luminaire of FIG. 4; and, FIG. 6 is a cross-sectional view of the luminaire of FIG. 4. The broken lines shown represent portions of the troffer luminaire that form no part of the claimed design.
